UNITED STATES PATENT OFFICE.

WILLIAM J. POOLE, OF LOS ANGELES, CALIFORNIA, ASSIGNOR TO AMERICAN LINEOGRAPH COMPANY, OF LOS ANGELES, CALIFORNIA, A CORPORATION OF CALIFORNIA.

TYPE-EJECTOR FOR TYPE-SETTING MACHINES.

1,177,894.

Specification of Letters Patent.

Patented Apr. 4, 1916.

Application filed October 13, 1913. Serial No. 794,854.

To all whom it may concern:

Be it known that I, WILLIAM J. POOLE, a citizen of the United States, residing at Los Angeles, in the county of Los Angeles, State 5 of California, have invented new and useful Improvements in Type-Ejectors for Type-Setting Machines, of which the following is a specification.

This invention relates to an improved 10 means of ejecting or transmitting type from the type magazine to the transfer or delivery chute of a type setting machine; specifically this invention relates to improvements in type setting machines of the general character 15 shown in my Patent No. 1,032,564 for type composing machines issued July 16th, 1912.

The prime object of my present invention is to provide means whereby a type may be 20 transmitted or ejected from the delivery end of the magazine into the transfer chute or equivalent in such manner and with such speed that the succeeding type cannot interfere with the delivered type. In a device 25 of the character described in my said patent there is a liability for the type to interfere and clog in the delivery chute when type are released in quick succession from the various magazines. The delivery chutes are 30 all brought to a common chute; and it is here that clogging by interference between type takes place. In order to obviate this interference and to provide for release of type in quick succession, it is necessary that there 35 be a certain minimum distance between type coming to the common chute. My present invention provides for this spacing of successive type by the means of giving the type such a velocity that one type will have 40 traveled a certain minimum distance when a successive type is released.

In a typical embodiment of my invention I use a sloping magazine down which the types gravitationally move to a point at the 45 upper end of the transfer chutes, there being a magazine channel for each of the chutes. The chutes are preferably vertical and the magazines preferably deliver the types in horizontal movement to the upper 50 ends of the chutes; and the delivered type is held in the upper end of the chute wholly within the chute and entirely free from the magazine. The weight of the body of type in the magazine tends to hold the single 55 delivered type against a means which keeps

the type from falling down the transfer chute. Said means is preferably of a yielding character; although it may be of any character to allow the type to drop down the transfer chute upon proper actuation. It 60 is the feature of this invention that the single delivered type held in the upper end of the transfer chute is quickly started in its downward movement and is quickly disengaged from the other type in the magazine. The single delivered type is given an initial impulse along the transfer chute by any efficient means; I have shown electromagnetic means to give the type a quick 65 downward impulse, freeing it from the holding means and from engagement and interference with the following type. The following type has only to move into the position occupied by the preceding type in order to be ready for delivery to the chute. This 70 movement is only equal to the thickness of the type body and may consequently take place very quickly. In fact, the next type assumes its proper position more quickly 75 than an operator can successively manipulate a key to cause successive operations of the same impulse magnet; the speed of setting type is limited only by the manual speed 80 of the operator manipulating the keys.

I have shown a preferred form and embodiment of my invention in the accompanying drawings, in which,

Figure 1 is a vertical longitudinal section showing the essential features of my invention, Fig. 2 is a front elevation of the 90 same, Fig. 3 is a detailed perspective showing the types as they are delivered from the magazine and showing the preferred means for holding a single type at the upper end of the transfer chute.

In the drawings the numeral 10 may designate a type holding magazine composed essentially of a plurality of inclined bars 12 with spaces 13 between them, the spaces 13 forming the channels through which the 100 types 14 pass. The lower ends of bars 12 are curved as at 15, so that the types are delivered practically in a horizontal direction to the upper ends of the transfer chutes. The types may engage with the bars 12 in 105 any preferred manner; it is only essential to my present invention that the types have certain shoulders 16 which ride over the bars 12 and which form the means by which the types are held at the upper ends of the 110

transfer chutes. In practice I cut notches or channels 17 on each side of the types, the upper sides of these notches forming the shoulders 16; and these notches lie loosely in engagement with the bars 12 of the magazine. With a sufficiently loose fit, the types slide easily down the magazine bars and move easily and quickly into place at the upper end of the transfer chutes.

10 The transfer chutes 20 (of the character shown in my said patent) are formed with a front wall 21 against which the types bear when they are delivered from the magazine. Division strips 22 form the side walls of the chutes 20, while back wall 23 may be formed in any convenient manner. When a type 14 is pressed forwardly in engagement with the front wall 21, it is entirely free of the magazine bars 12 and is no longer held from 15 downward movement by engagement therewith. Opposite the delivery point of each magazine channel I place a means which engages with one of the shoulders 16 of the type to hold it from dropping down the chute until desired; and, although other means may be used, this holding means preferably takes the form of a yielding device in the form of a small spring 30 with a curved lower end projecting in under the shoulder 16. It will be understood that I 20 may use such a yielding or releasable means in engagement with any part or any shoulder on the type; for convenience and simplicity I prefer to use the shoulder 16. As a type moves off the end of the magazine it moves over the lower curved end of the spring 30 and is held by the spring against downward movement. The weight of the body of type 25 back of the single type holds the single type in engagement with the spring. The single type is releasably held wholly in the transfer chute and entirely free of the magazine.

My preferred means for giving each type an initial impulse is electro-magnetic in its 30 nature. Other impulse means may be used; the electro-magnetic means is simple and effective in operation and control. I employ a small solenoid 35 whose plunger core 36 is normally held in position by a small spring 37. A plunger rod 38 carries a plunger 39 at its lower end. Plunger 39 may preferably be made of some material which will not injure the face of the type, such as fiber or the like. The action of the 35 solenoid is controlled by any suitable key arrangement. When the solenoid is energized it immediately pulls its core downwardly, causing the plunger 39 to push the type 14 downwardly and to accelerate the type quickly; giving the type an initial impulse along the transfer chute. The plunger 39 preferably follows the type through a considerable movement, equal to almost the length of the type. As the plunger withdraws, the next type is in position to take

the place of the delivered type and the instant the plunger passes above the heads of the type, the next type moves into position. It is seen that this movement is only equal to the thickness of the type and that the 40 next type is quickly positioned ready for a subsequent operation of the plunger. The plunger will normally stand only a very short distance above the tops of the type; so that, rather than being struck, the types are pushed downwardly and given a gradual acceleration instead of being struck forcibly by the plunger. The acceleration given the type may be suited to conditions. I have found that gravitational acceleration 45 is not sufficient to advance a preceding type to a point where it will not be interfered with by a succeeding type when the machine is working at high velocity. I have found that a substantial initial acceleration, superimposed upon the gravitational acceleration, will entirely obviate interference.

As the transfer chutes and individual magazines are necessarily quite close together, I arrange to place the magnets 50 in tiers above each other; the plunger rods 38 being offset so as to reach the respective types upon which the plungers 39 operate. There will be a separate magnet and plunger for each magazine and transfer chute. 55 Any preferred means may be used for controlling the electro-magnets; such means being shown in my said issued patent.

My invention accomplishes the object hereinbefore set forth and eliminates all interference between types successively delivered from the several magazines. It is impossible for the type from one magazine to interfere and clog the transfer chute for the reason that one type must necessarily be entirely out of the way before a succeeding type can come into place and before the succeeding type can be started along the transfer chute. Giving the type an initial impulse causes it to be in a position at some distance along the chute before the next type from the same or from another magazine can be started. A succeeding type cannot possibly catch a preceding type, because the velocity of movement is great enough to put a considerable space between two successively delivered types even in the short time interval between their releases. As hereinbefore stated, the time interval between successive releases of type is exceedingly small; so small that the operation is completed faster than an operator can manipulate a key. The speed of the machine is limited only by the speed ability of the operator manipulating the keys.

I claim—

1. In a type setting machine or the like, a vertical transfer chute, a magazine delivering shouldered type to the upper end of said chute in a horizontal direction, said maga-

zine being downwardly inclined so that the type presses toward the chute, a spring in the wall of the transfer chute opposite the magazine delivery, said spring adapted to engage under the shoulder of a delivered type and said type pressed into engagement with the spring by pressure of the other type in the magazine, and means to give said type an initial impulse down the transfer chute.

2. In a type setting machine or the like, a vertical transfer chute, a magazine delivering shouldered type to the upper end of said chute in a horizontal direction, said magazine being downwardly inclined so that the type presses toward the chute, and said magazine ending at the near wall of the chute, a spring in the wall of the transfer chute opposite the magazine delivery, said 15 spring adapted to engage under the shoulder of a delivered type and said type pressed into engagement with the spring by pressure of the other type in the magazine, said delivered type being wholly in the chute and 20 free of the magazine, and means to give said type an initial impulse down the transfer chute.

3. In a type setting machine or the like, a downwardly extending transfer chute, a 25 magazine delivering type to the upper end of the transfer chute, yielding means to hold a single type in the transfer chute clear of the magazine, said means adapted to yield to forced movement of the type along the 30 transfer chute, and means to give said type an initial impulse along the transfer chute, to free it of the holding means and to give it a substantial initial velocity along the chute, said means including an electro-magnet and a plunger operated thereby to move 35 against the type.

4. In a type setting machine or the like, a vertical transfer chute, a magazine delivering shouldered type to the upper end of said 40 chute in a horizontal direction, said magazine being downwardly inclined so that the type presses toward the chute, a spring in the wall of the transfer chute opposite the magazine delivery, said spring adapted to 45 engage under the shoulder of a delivered type and said type pressed into engagement with the spring by pressure of the other type in the magazine, and means to give said type an initial impulse down the transfer chute, said means including an electro-magnet and a plunger operated thereby to move 50 against the type.

5. In a type setting machine or the like, a vertical transfer chute, a magazine delivering shouldered type to the upper end of said chute in a horizontal direction, said magazine being downwardly inclined so that the type presses toward the chute, and said magazine ending at the near wall of the chute, a spring in the wall of the transfer 55

chute opposite the magazine delivery, said spring adapted to engage under the shoulder of a delivered type and said type pressed into engagement with the spring by pressure of the other type in the magazine, said delivered type being wholly in the chute and free of the magazine, and means to give said type an initial impulse down the transfer chute, said means including an electro-magnet and a plunger operated thereby to 70 move against the type.

6. In a type setting machine or the like, a vertical transfer chute, a magazine delivering shouldered type to the upper end of said chute in a horizontal direction, a 75 spring adapted to engage under the shoulder of the type to hold it from falling down the chute, and means for giving the type an impulse down the chute sufficient to release it from said spring and to give it a substantial initial velocity down the chute.

7. In a type setting machine or the like, a downwardly extending transfer chute, a magazine delivering type to the upper end of the transfer chute, yielding means to hold a single type in the transfer chute clear of the magazine, said yielding means adapted to yield to forced movement of the type along the transfer chute, and means for releasing the type, said means including an electro-magnet and a plunger operated thereby to strike the type and release it soon after its impact therewith and thereafter to give the type a substantial initial impulse along said transfer chute.

8. In a type setting machine or the like, a transfer chute, a type magazine delivering type to the transfer chute, yielding means for holding a type delivered by the magazine ready to move along the chute, said yielding means adapted to yield under the forced movement of the type along the chute, and means for forcing said type along the chute to release it from the yielding means and thereafter to give the type a substantial initial velocity along the chute.

9. In a type setting machine or the like, a vertical transfer chute, a magazine delivering shouldered type to the upper end of said transfer chute in a horizontal direction, said magazine being downwardly inclined so that the type presses toward the chute, a yielding member in the wall of the transfer chute opposite the magazine delivery, said member adapted to engage the shoulder of a delivered type and said type pressed into engagement with the member by pressure of the other type behind it, and means to give said type an initial impulse down the transfer chute.

10. In a type setting machine or the like, a vertically extending transfer chute, a magazine delivering type to the upper end of the chute in a horizontal direction, said magazine being downwardly inclined so 125

that the type presses toward the chute, a yielding member in the wall of the chute opposite the magazine delivery adapted to engage and releasably hold a delivered type for movement down the chute, said yielding member adapted to yield to forced movement of the type along the chute, and means for forcing said type downwardly along the chute to release it from said yielding means

and thereafter to give it a substantially initial velocity along the chute.

In witness that I claim the foregoing I have hereunto subscribed my name this 2nd day of October, 1913.

W. J. POOLE.
